CLAIM

The ornamental design for the float for walking on water, as shown and described.

DESCRIPTION

FIG. 1 is a perspective view of the float for walking on water, showing my new design.

FIG. 2 is a front elevation view thereof.

FIG. 3 is a rear elevation view thereof.

FIG. 4 is a right side elevation view thereof.

FIG. 5 is a left side elevation thereof.

FIG. 6 is a top view thereof; and,

FIG. 7 is a bottom view thereof.

The broken lines showing of a floater and feet securing devices in FIG. 1 depict environmental subject matter and form no part of the claimed design.

1 Claim, 7 Drawing Sheets
